(57) **CLAIM**

The ornamental design for a combined stuffed animal and box, as shown and described.

DESCRIPTION

FIG. 1 is a top perspective view of a combined stuffed animal and box, showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a cross section view of the combined stuffed animal and box taken along line 8-8 of FIG. 1;

FIG. 9 is a cross section view of the combined stuffed animal and box taken along line 9-9 of FIG. 1;

FIG. 10 is a cross section view of the combined stuffed animal and box taken along line 10-10 of FIG. 1; and,

FIG. 11 is a cross section view of the combined stuffed animal and box taken along line 11-11 of FIG. 1.

The broken lines showing depict portions of the combined stuffed animal and box that form no part of the claimed design.

The use of stippling indicates a contrasting appearance with the adjacent line-shaded portion of the claimed design.
